US00D943903S

(12) **United States Design Patent** (10) Patent No.: **US D943,903 S**
(45) Date of Patent: **** Feb. 22, 2022**

(54) **SHOE**

(71) Applicant: **Reebok International Limited**, London (GB)

(72) Inventors: **Dennis Gaboriault**, Millbury, MA (US); **Matthew Costa**, Mattapoisett, MA (US); **Dustin Simone**, Mansfield, MA (US)

(73) Assignee: **Reebok International Limited**, London (GB)

(**) Term: **15 Years**

(21) Appl. No.: **29/785,079**

(22) Filed: **May 24, 2021**

Related U.S. Application Data

(63) Continuation of application No. 29/708,149, filed on Oct. 3, 2019, now Pat. No. Des. 922,044.

CLAIM

The ornamental design for a shoe, as shown and described.

DESCRIPTION

FIG. 1 is a bottom perspective view of a shoe showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the figures show portions of the shoe that form no part of the claimed design.

1 Claim, 6 Drawing Sheets
